UNITED STATES PATENT OFFICE

167,119

IRONER STAND

Allen T. Shott, Cincinnati, Ohio

Application April 15, 1952, Serial No. 19,325

Term of patent 7 years

(Cl. D49—3)

To all whom it may concern:

Be it known that I, Allen T. Shott, a citizen of the United States, residing at Cincinnati, in the county of Hamilton, State of Ohio, have invented a new, original, and ornamental Design for an Ironer Stand, of which the following is a specification, reference being had to the accompanying drawing, forming a part thereof.

I claim:

The ornamental design for an ironer stand, substantially as shown.

ALLEN T. SHOTT.
